UNITED STATES PATENT OFFICE.

THEODORE J. KINTNER, OF DENVER, COLORADO.

GAGE ATTACHMENT FOR PLANES.

1,110,999.

Specification of Letters Patent.

Patented Sept. 15, 1914.

Application filed April 9, 1913. Serial No. 759,863.

To all whom it may concern:

Be it known that I, THEODORE J. KINTNER, a citizen of the United States, residing at Denver, in the county of Denver and State of Colorado, have invented certain new and useful Improvements in Gage Attachments for Planes, of which the following is a specification.

This invention relates to improvements in gages of the type used on jointer-planes to guide them in their longitudinal movement so that they will cut the piece to be planed, at a definite angle with respect to a side thereof, and the principal object of the invention resides in the provision of adjustable means of simple and novel construction whereby a gage of this character may be readily attached to planes of different proportions.

10 An embodiment of my invention has been illustrated in the accompanying drawings in the various views of which like parts are similarly designated, and in which,

Figure 1, represents a perspective view of a plane with my improved gage in its operative position. Fig. 2, an enlarged section taken along the line 2—2, Fig. 1, and Fig. 3 a fragmentary section taken along the line 3—3, Fig. 2.

30 Referring to the drawings by numerical reference characters, 2 designates a metal jointer-plane which comprises as usual, a sole plate 3 provided with parallel sides 4 which extend upwardly along its longitudinal edges and which are connected at a point in front of the cutter 5, by a transverse rib 6. The edges of the sides 4 curve from their ends, convergently to intermediate enlargements 7 between which the 40 cutter 5 and the frog 8 are transversely disposed, and the plane is as usual, provided with a handle or tote 9 and a hand-knob 10.

My improved gage consists of an oblong block 14 made of wood or other suitable material which at a point between its ends has a transverse seat 12 which, in practice, engages the sole of the plane and whose outer edge is beveled as at 13, to clear the cutting edge of the bit 8 which projects 50 through the mouth in the bottom-plate of the tool.

The block 14 carries at points above the seat 12, two longitudinally adjustable members 15 and 16 which coöperate to rigidly secure it in its proper position with relation to the plane, in which position the seat 12

engages the sole of the latter, as is shown in the drawings. The smaller one, 16, of the two members consists of a longitudinally slotted plate which is guided in its longitudinal adjustment by a pair of screws 17 which project through its slot, into threaded apertures in the block and which may singly or jointly be tightened to firmly secure the member in its adjusted position. The other, 60 larger member 15, consists of a longitudinally slotted bar, the lower end of which is bifurcated to straddle the transverse rib 6 of the plane. It is guided in its longitudinal adjustment by means of two screws 18 and 19 which extend through its slot, into threaded apertures in the block, and one of these screws, 19, is provided with a thumb-head and serves as a set screw to secure the bar in its adjusted position. The 65 upper end of the bar is milled as shown at 21 in the drawings, to facilitate its manipulation.

To fasten the gage in its proper position on the plane, the screws which normally 80 secure the adjustable members 15 and 16, are loosened and the block is placed against the outer surface of one of the sides of the tool with its seat 12 in engagement with the sole of the same, and so that the plate 85 16 rests upon the slanting edge of the said side, while the bifurcated end of the bar 15 straddles the cross-rib of the plane. The members 15 and 16 are now clamped in their adjusted positions by tightening the 90 screws which extend through their longitudinal slots and the gage is thereby securely fastened to the plane with the inner surface of its portion below the seat 12 at right-angles to the sole of the tool, for engagement 95 with the side of the piece of work whose edge is being planed.

To remove the gage from the plane it is but necessary to loosen the larger member 15 and move it upwardly to disengage the 100 rib 6 and by leaving the other member 16 in place, the gage may at any time be immediately replaced in its proper position on the plane, by merely sliding the block along the side thereof until its progress is arrested 105 by the engagement of the lower end of the member 16 with the sloping edge of the said side, when, by the engagement of the slanting rearward side of the slit in the lower end of the member 15 with the upper edge 110 of the rib 6, the block is, as hereinbefore described, drawn rearwardly until it has

reached the same position it formerly occupied, when by means of the set-screw 19 it is again securely fastened to the tool.

Having thus described my invention what I claim and desire to secure by Letters-Patent is:

1. In a gage attachment for planes having a transverse rib, a body part having a seat to engage the sole of a plane, and at opposite sides of said seat, a guiding surface for engagement with the work and an abutment surface for engagement with the side of the plane, a member on said body part for engagement with the edge of said side, and an adjustable member on said body part, having at one of its ends a slit adapted to receive the said rib of the plane.

2. In a gage attachment for planes having a transverse rib, a body part having a seat to engage the sole of a plane, and at opposite sides of said seat, a guiding surface for engagement with the work and an abutment surface for engagement with the side of the plane, and two members adjustable on said body part and adapted to respectively engage the edge of the said side and straddle the said rib of the plane.

3. In a gage attachment for planes having a transverse rib, a body part having a seat to engage the sole of a plane, and at opposite sides of said seat, a guiding surface for

engagement with the work and an abutment surface for engagement with the side of the plane, a member on said body part for engagement with the edge of said side, a second member slidably mounted on said body part, and having in one of its ends a slit which is adapted to receive the said rib of the plane and which has a slanting surface to engage the upper edge of said rib when said second member is moved toward the same, and means for securing said second member in its adjusted positions.

4. In a gage attachment for planes having a transverse rib, a body part having a seat to engage the sole of a plane, and at opposite sides of said seat, a guiding surface for engagement with the work and an abutment surface for engagement with the side of the plane, two members slidable on said body part in the direction of its seat, and means for securing said members in their adjusted positions, one of said members being adapted to engage the edge of the side of a plane and the other having a slit adapted to receive the said rib of the same.

In testimony whereof I have affixed my signature in presence of two witnesses.

THEODORE J. KINTNER.
